CLAIM

The ornamental design for an combination airplane-shaped container and lip balm, as shown and described.

DESCRIPTION

FIG. 1 is a perspective view of the combination airplane-shaped container and lip balm;

FIG. 2 is a front side view thereof;

FIG. 3 is a rear side view thereof;

FIG. 4 is a left side view of the combination airplane-shaped container and lip balm, the right side view being a mirror image thereof;

FIG. 5 is a top side view thereof; and,

FIG. 6 is a bottom side view thereof.

The broken lines illustrate portions of the combination airplane-shaped container and lip balm that form no part of the claimed design. The dash-dot broken lines illustrate a boundary of the claimed design and forms no part thereof.

1 Claim, 6 Drawing Sheets
